UNITED STATES PATENT OFFICE.

JOHN W. ACHARD, OF PHILADELPHIA, PENNSYLVANIA.

END-CELL SWITCH.

1,201,418.

Specification of Letters Patent. Patented Oct. 17, 1916.

Application filed November 2, 1911. Serial No. 658,245.

To all whom it may concern:

Be it known that I, JOHN W. ACHARD, a citizen of the United States, and a resident of Philadelphia, county of Philadelphia, 5 State of Pennsylvania, have invented certain new and useful Improvements in End-Cell Switches, of which the following is a specification.

My invention relates to switches in which 10 a movable contacting member coöperates with a series of contacts connected to the intermediate points in a series of storage battery cells, and especially to such switches in which auxiliary resistances are employed on 15 either side of the contacts to prevent opening the circuit when the movable member travels from one contact to the next, and at the same time to prevent an excessive flow of current when the movable member 20 is located between two contacts. Auxiliary contact blocks of comparatively high resistance have been used for this purpose made of material such as graphite or carbon. In some cases, however, it is found desirable 25 that the resistance of such auxiliary contacts shall increase rapidly as the moving member recedes from the main contact, and a solid block is not found satisfactory in this respect. In order to obtain this result, in 30 accordance with my invention, I provide a plurality of laterally arranged blocks of comparatively high resistance, and of such material as will also offer an appreciable resistance across the contact surfaces between 35 adjacent blocks. I utilize this contact resistance to secure the desired results, and also provide means for adjusting the value of this resistance.

My invention will be more clearly understood by reference to the following description taken in connection with the accompanying drawings in which—

Figure 1, is a diagrammatic view of an end cell switch embodying features of my 45 invention, with its circuit connections. Fig. 2, is a section of one of the contacts along the line A A of Fig. 1, drawn to an enlarged scale. Fig. 3, is a plan view of one of the contacts, and Fig. 4, is a section taken along the line X X of Fig. 3.

Referring to Fig. 1, B is a storage battery connected at one terminal to conductor 1 of the consumption circuit 1—7, while the other terminal, and several intermediate

points of the battery are connected respectively to contacts 2, 3, 4, 5 and 6 of an end cell switch. A traveling brush D operated by means of a screw E, and a crank F connects any one of the several contacts to the continuous conducting bar C, which is connected to the opposite conductor 7 of the consumption circuit. The brush D is narrower than the space between two main contacts, such as 4 and 5, but these contacts are provided with laterally disposed auxiliary contact blocks 11, which partially bridge the gap between adjacent contacts, and prevent the circuit from being opened as the brush moves from one contact to the next. These auxiliary contacts 11 consist of a series of blocks which may be of carbon or graphite. They are shown on a larger scale in the sectional view given in Fig. 2. Referring to this figure, the main contact, which may be made of conducting metal, such as copper, is forked to receive a block of high resistance material, such as carbon, this latter being shown at 9. The upper and lower portions of the fork are shown in section at 8^a and 8^b. The bolts 10 serve to clamp the upper and lower members of the fork in good contact with the carbon block 9. The block 9 extends on either side of the fork, being notched to receive the fork so that the upper and lower surfaces of the fork, and the carbon block, are flush. Laterally attached to the carbon block 9, by means of bolts 12, are shown auxiliary carbon blocks or laminations 11, whose upper and lower surfaces are also flush with the surface of the main block 9, and the fork 8^a and 8^b. A metallic plate 15 is shown under the nuts of the bolts 12 to distribute the pressure, and the bolts are themselves insulated from the laminations 11 by means of insulating sleeves 13, and from the metallic plate 15 by means of insulating washers 14.

Referring again to Fig. 1 it will be seen that as the traveling brush D leaves one of the main contacts, the current which it carries must pass through the auxiliary blocks or laminations 11, and as the motion of the brush continues, the contact resistances between the auxiliary contact block 9, and the adjacent lamination, as well as between the laminations themselves are successively thrown into circuit, thus increasing the circuit resistance rapidly with a small travel of

the brush. Similarly as the brush approaches one of the contacts, the resistance, which is high at first, is rapidly reduced as the contact resistances between the surfaces 5 of the carbon blocks are cut out of circuit. The resistances between these surfaces vary with the pressure, and these resistances may, therefore, be adjusted by adjusting the pressure produced between the contact surfaces 10 by the bolts 12. An adjustment may also be effected by means of longitudinal grooves or recesses 16 which reduce the area of contact. By adjusting the width of these grooves the contact resistance may be adjusted as desired. 15 Fig. 3 is a plan view of one of the contacts showing the details on a larger scale, the same reference numbers being used to designate corresponding parts.

Fig. 4 is a sectional view along the line 20 X X of Fig. 3, showing more clearly the construction of the fork of the main contact.

Having described my invention, what I

claim and desire to secure by Letters Patent is—

1. A switch having in combination a main contact and a series of interfacially grooved contact resistance laminations in permanent contact with each other, and whereof one is in permanent contact with the main contact, substantially as described. 25

2. A switch contact having in combination a main contact and a series of contact resistance laminations in permanent contact with each other, and whereof one is in permanent contact with the main contact, and means 30 for adjusting the contact pressure of said laminations. 35

In testimony whereof I have hereunto signed my name in the presence of two witnesses.

JOHN W. ACHARD.
